UNITED STATES PATENT OFFICE.

EUGENE A. BAGBY, OF CINCINNATI, OHIO.

COLLAPSIBLE ASH-PAN AND ADJUSTABLE HOPPER FOR THE SAME.

No. 836,002.

Specification of Letters Patent.

Patented Nov. 13, 1906.

Application filed November 29, 1905. Serial No. 289,615.

To all whom it may concern:

Be it known that I, EUGENE A. BAGBY, a citizen of the United States, and a resident of Cincinnati, in the county of Hamilton and State of Ohio, have invented a new and Improved Collapsible Ash-Pan and Adjustable Hopper for the Same, of which the following is a full, clear, and exact description.

The invention relates to open grates, stoves, ranges, and the like; and its object is to provide a new and improved collapsible ash-pan and a hopper for the same, the hopper being arranged to properly fit different-sized grates to receive all the ashes dropped down from the grate and to guide the ashes into the ash-pan, the latter being extensible to form a bucket for carrying the ashes conveniently to a place of discharge.

The invention consists of novel features and parts and combinations of the same, which will be more fully described hereinafter, and then pointed out in the claims.

A practical embodiment of the invention is represented in the accompanying drawings, forming a part of this specification, in which similar characters of reference indicate corresponding parts in all the views.

Figure 1 is a perspective view of the improvement, showing the ash-pan collapsed and the hopper in position thereon. Fig. 2 is a like view of the ash-pan extended to form a bucket, the hopper being removed. Fig. 3 is a reduced perspective view of the extensible hopper; and Fig. 4 is an enlarged cross-section of the improvement, showing the pan collapsed and the hopper nested therein.

The collapsible ash-pan A, made, preferably, of sheet metal, consists of a bottom section A', a middle section A², and a top section A³, the latter being provided on opposite sides with lugs B, engaged by the ends of a bail C to permit of conveniently carrying the ash-pan from place to place. The bottom section A' of the ash-pan is in the form of a box or tray open at the top, while the middle and top sections A² and A³ are in the shape of open frames. The bottom section A' is provided at its upper end with outwardly-extending flanges A⁴, adapted to be seated on inwardly-extending flanges A⁵, formed on the lower end of the middle section A², and the top of the latter is provided with outwardly-extending flanges A⁶, adapted to rest on inwardly-extending flanges A⁷, formed on the lower end of the top section

A³. Now by lifting the top section A³ by the use of the bail C it is evident that the middle section A² and the bottom section A' slide downward until the flanges A⁶ are seated on the flanges A⁷ and the flanges A⁴ are seated on the flanges A⁵—that is, the several sections are extended to form a bucket of considerable depth to permit of conveniently carrying the ashes from the grate to a suitable place of discharge.

The ashes can be conveniently dumped out of the bucket, and in order to prevent the lower or bottom section A' from sliding out of the middle section A² the latter is provided at its top with inwardly-extending lugs A⁸, extending over the top flanges A⁴ of the bottom section A', as plainly indicated in Figs. 2 and 4. In order to prevent the middle section A² from sliding out of the top section A³ at the time the ashes are dumped, the said top section A³ is provided at its upper end with a broad inwardly-extending flange A⁹ reaching over the flange A⁸, as will be readily understood by reference to Fig. 4.

An extensible hopper D is adapted to be set in the upper section A³, as plainly illustrated in Fig. 1, and this hopper has its sides inclined and is made extensible to allow of increasing the size of the hopper or decreasing the same to properly fit the size of the grate on which the device is to be used. Thus the ash-pan A may be considerably smaller than the grate; but by using the hopper D and extending the same properly to the full size of the grate it is evident that the ashes dropping down from the grate are directed by the hopper D into the ash-pan A, and consequently no ashes are liable to fall outside of the ash-pan. In a like manner the hopper D can be folded to such small size as to be conveniently nested within the folded or telescoped ash-pan to allow of conveniently shipping both the pan and the hopper, as will be readily understood by reference to Fig. 4. For the purpose mentioned the hopper D is made of L-shaped sections D', the adjacent members of the sections overlapping each other, and each member is provided with one or more guide-lugs D², engaging the other member to allow of conveniently sliding one member upon the other, thus permitting convenient increase or decrease in the size of the hopper to allow of fitting the hopper to the grate on which the ash-pan and the hopper are to be used. After the hopper

is fitted to the size of the grate the lugs D² may be hammered down, so as to firmly lock the members of the sections D' to form a hopper fitting the size of the grate.

5. When the hopper is in use on the ash-pan A and the parts are in position under the grate with the ash-pan in a collapsed condition, then the hopper D practically doubles the capacity of the ash-pan—that is, allows 10 storing of a large quantity of ashes in the pan and hopper—and at the same time the hopper directs the ashes to the middle of the pan and prevents overflow of ashes from the pan.

The ash-pan and hopper thereon containing 15 the ashes can be readily removed from the place of use by the operator taking hold of the bail C, and then the operator by lifting the bail allows the ash-pan sections A² and A' to drop, so as to form a bucket of the ash-pan 20 to allow of conveniently carrying the ashes to a suitable place of discharge.

If desired, the middle section A² may be omitted and the bottom section A' made to telescope in the upper section A³.

25 Having thus described my invention, I claim as new and desire to secure by Letters Patent—

1. An ash-pan and hopper for the same, comprising a pan formed of sections telescoping 30 one in the other, one of the sections being in the form of a tray, and a hopper fitting upon the upper section of the pan, said hopper being extensible whereby the hopper can be extended to fit different-sized grates and 35 contracted to be nested in the pan when the said pan is not in use and folded.

2. An ash-pan and hopper for the same, comprising a pan formed of sections telescoping 40 one in the other, one of the sections being in the form of a tray, and a hopper having inclined sides and fitting upon the upper section of the pan, said hopper being formed of sections sliding one upon the other, whereby 45 the hopper can be extended to fit the grate with which the pan is used or folded to fit within the pan when the said pan is not in use.

3. An ash-pan and hopper for the same, comprising a pan formed of three angular sections 50 telescoping one in the other, the bottom section being in the form of a tray and the other two open frames, the upper section being provided with a bail, and a hopper having inclined sides and fitting upon the upper section of the pan, said hopper being formed of sections sliding one upon the other to permit the size of the hopper to be increased or decreased.

4. A hopper for an ash-pan made in L-shaped flaring sections having their members 60 in sliding engagement with each other to

allow of increasing or decreasing the size of the hopper.

5. A hopper for an ash-pan made in L-shaped flaring sections, the adjacent members of the sections overlapping each other to form a rectangular structure, and guide-lugs on the said overlapping members to allow of sliding one on the other to extend or reduce the hopper. 65

6. An ash-pan made in sections telescoping one in the other, the bottom section being in the form of a box open at the top and having an outwardly-extending flange at its upper end, the middle section being in the form 70 of an open frame and having an inwardly-extending flange at its lower end and an outwardly-extending flange at the upper end, and the upper or top section being in the form of an open frame having an inwardly-extending flange at its lower end and at its upper end a like flange projecting over the top of the middle section. 75

7. An ash-pan made in sections telescoping one in the other, the bottom section being 80 in the form of a box open at the top and having an outwardly-extending flange at its upper end, the middle section being in the form of an open frame and having an inwardly-extending flange at its lower end and an outwardly-extending flange at the upper end, 85 said middle section also having inwardly-extending lugs at its top and the upper or top section being in the form of an open frame having an inwardly-extending flange at its lower end and a like flange at its upper end projecting over the top of the middle section 90 to prevent the said middle section from falling out. 95

8. An ash-pan made in sections telescoping one in the other, the bottom section being in the form of a box open at the top and having an outwardly-extending flange at its upper end, the middle section being in the form of an open frame and having an inwardly-extending flange at its lower end and an outwardly-extending flange at the upper end, 100 and the upper or top section being in the form of an open frame having an inwardly-extending flange at its lower end, the said 105 middle section having inwardly-extending lugs to hold the lower or box section from falling out when dumping the contents of the pan. 110

In testimony whereof I have signed my 115 name to this specification in the presence of two subscribing witnesses.
